UNITED STATES PATENT OFFICE.

JACOB JACKSON CORNELL, OF PADUCAH, KENTUCKY.

WHISTLE.

Application filed May 23, 1922. Serial No. 563,041.

To all whom it may concern:

Be it known that I, JACOB J. CORNELL, a citizen of the United States of America, and resident of Paducah, in the county of McCracken and State of Kentucky, have invented certain new and useful Improvements in Whistles, of which the following is a specification.

This invention relates to whistles or horns such as are used by automobilists, the said invention having relation more particularly to a whistle intended to be operated from the exhaust of the motor of an automobile; the said invention having for an object the provision of novel means whereby the course of travel of the exhaust may be diverted and caused to pass through the whistle, or the device may be so operated as to divert only a portion of the exhaust, in order that the whistle can be blown with greater or less force, according to the operation of the controlling mechanism.

It is a further object of this invention to produce a coupling to be interposed in the exhaust line, associated with a valve and valve operating mechanism, adapted to control the passage of the exhaust through the whistle.

It is a further object of this invention to provide novel means for equalizing the operation of the valve with relation to the valve seat, in order that the valve may properly seat through its oscillatory movement, as will presently appear.

It is a further object of this invention to provide a coupling of the character indicated, associated with a horn body provided with a nipple that terminates in a valve seat, with relation to which the valve operates, and to produce a device of the character indicated having advantages in points of efficiency and simplicity.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in elevation, partly in section, showing a whistle embodying the invention;

Figure 2 illustrates an end view of the coupling, showing a valve and its operating mechanism and a fragment of the whistle in elevation;

Figure 3 illustrates a top plan view of the whistle;

Figure 4 illustrates a sectional view of one of the whistle tubes; and

Figure 5 illustrates a view in elevation of a fragment of the whistle showing its application to the coupling.

In these drawings 10 denotes a tubular member or coupling which is adapted to be interposed in the exhaust line in any appropriate location, the said coupling having an opening 11, the wall of which is threaded and constitutes a seat for the nipple 12 of the horn body 13, the said horn body being supplied with a plurality of tubes 14, 15, 16, 17 and 18 of different lengths, in order that the tones may be varied according to the lengths of the tubes and the openings in the tubes, as will be understood. As the principle of the horn is well known, it is believed unnecessary to describe the details of the body and tubes, except in a general way.

The nipple 12 projects beyond the inner wall of the coupling and terminates in a valve seat 19 and it is, of course, intended that the exhaust shall escape through the nipple into the body of the horn.

As a means for controlling and diverting the course of travel of the exhaust through the coupling, a valve 20 is installed in the coupling in a manner to bear against the valve seat, so as to close the opening through the nipple, or the said valve may be moved to almost wholly obstruct the passage through the coupling when the nipple is opened, in order that the exhaust will be caused to travel through the nipple and horn. As a means for mounting the valve so that it will oscillate to engage the seat or to close or partially close the passage through the coupling, a post 21 is applied to the coupling and it extends through an aperture 22 therein to the interior of the said coupling, and the said post carries a pivot 23 on which the valve oscillates. The post has a head 24 and a spring 25 encircles the post, bearing against the head and coupling to yieldingly hold the head in its outwardly projected position.

A link 26 is pivoted to the side of the valve remote from the point where it is pivoted to the post, and this link in turn is pivotally connected to an operating rod 27 that reciprocates through a guide 28 threaded in the coupling. A collar 29 is adjustably secured on the rod, and a spring 30 encircles the rod and is interposed between the guide 28 and the said collar, acting to force the rod normally outward to hold the valve in engagement with the valve seat of the nipple. The operating rod may be extended to suit particular requirements, in order that it will terminate within convenient reach of an operator, and it may be supplied with any suitable handle 31, although I prefer to have the body in sections with a screw joint 13^a to permit the body to be separated for the purpose of cleaning its interior.

As the parts are arranged, the valve is held normally closed by the spring 30, and when the operator desires to sound the whistle, he will force the rod inwardly and move the valve and its operating parts to the dotted line positions shown in Fig. 1, or to some modified degree, according to the amount of noise that is desired, whereas upon release of pressure from the rod, the spring will act to automatically seat the valve.

The purpose of the yieldable post is to cause an equalization of the parts so that the valve will always properly seat when pressure is removed from the rod.

By reason of the adjustment afforded by the collar 29, the tension of the spring may be changed.

In the modification shown in Fig. 5, the coupling 32 and the interior mechanism and the device for operating the interior mechanism will be the same as that heretofore described, except that instead of having the nipple on the horn body as heretofore described, the horn body 33 will be connected by an elbow 34 to the coupling, and the elbow 34 may have a suitable nipple or extension projecting into the coupling 32 and terminating in a valve seat, similar to that heretofore described. The provision of the modified construction results in permitting the horn to lie horizontally instead of at right angles to the longitudinal axis of the coupling.

I claim:

1. In an exhaust whistle, a coupling adapted to be inserted in an exhaust line, a nipple threaded in the coupling and having a valve seat on its inner end, a horn body adapted to carry tubes, a yieldable post extending through the coupling, a valve oscillatably mounted thereon in position to engage the valve-seat of the nipple, and a rod connected to the valve remote from the post for moving the valve into and out of engagement with the seat. 55

2. In an exhaust whistle, a coupling, a horn body having a nipple extending through the coupling, a valve coacting with the end of the nipple to open and close the same, a yieldable post, means for oscillatably mounting the valve on the post, and means connected to the valve for oscillating the valve. 70

3. In an exhaust whistle, a coupling, a horn body having a nipple extending through the coupling, a valve coacting with the end of the nipple to open and close the same, a yieldable post on which the valve is oscillatably mounted, means for oscillating the valve, a link connected to the valve, and a rod to which the link is connected and by which the valve is operated. 75

4. In an exhaust whistle, a coupling, a horn body having a nipple extending through the coupling, a valve coacting with the end of the nipple to open and close the same, a yieldable post on which the valve is oscillatably mounted, means for oscillating the valve, a link pivotally connected to the valve, a rod to which the link is pivoted, a guide carried by the coupling in which the rod is slidable, and means for forcing the rod outwardly. 85

5. In an exhaust whistle, a coupling, a horn body having a nipple extending through the coupling, a valve coacting with the end of the nipple to open and close the same, a yieldable post on which the valve is oscillatably mounted, means for oscillating the valve, a link pivotally connected to the valve, a rod to which the link is pivotally connected, a guide through which the rod is slidable, an abutment on the said rod, and a spring encircling the rod interposed between the guide and the abutment. 95

JACOB JACKSON CORNELL.
